UNITED STATES PATENT OFFICE.

THEODORE SZYLDEROWICZ, OF SHAMOKIN, PENNSYLVANIA.

VISE.

1,406,102.

Specification of Letters Patent. Patented Feb. 7, 1922.

Application filed November 11, 1920. Serial No. 423,430.

To all whom it may concern:

Be it known that I, THEODORE SZYLDEROWICZ, a citizen of the United States, and a resident of Shamokin, in the county of 5 Northumberland, and State of Pennsylvania, have invented a new and Improved Vise, of which the following is a full, clear, and exact description.

This invention relates to improvements in 10 vises, an object of the invention being to provide the jaws of the vise with conical extensions, said extensions curved in cross-section and tapering to their outer ends so that a wire or other device can be conveniently bent around either or both of the extensions and the bend be given the desired 15 arc, coil, or curvature by reason of its location between the extensions.

A further object is to provide a vise which 20 is capable of performing all the functions of the ordinary vise and which, in addition, is provided with extensions which facilitate the bending operation of wires and other metal devices.

25 With these and other objects in view the invention consists in certain novel features of construction, and combinations and arrangements of parts, as will be more fully hereinafter described and pointed out in the 30 claims.

In the accompanying drawings—

Figure 1 is a view in side elevation illustrating my improved vise.

Figure 2 is a top plan view.

35 Figure 3 is a fragmentary view in front elevation.

1 represents the base of the vise which is clamped to a table or other support 2 and provided with a standard 3 having a fixed 40 jaw 4 thereon. 5 is a bar mounted to slide through the standard 3 and on one end of this bar 5 a movable jaw 6 is located, and an adjusting screw 7 engages the standard 3, extends through the jaw 6 and is provided 45 with an operating device at one end as is customary in this art.

The jaws 4 and 6 are provided with laterally projecting extensions 9, 9. These extensions are of conical shape, circular in 50 cross-section presenting curved faces, said curved faces gradually diminishing in arc

or curvature from their inner to their outer ends so that a wire or other piece of metal can be inserted between the extensions, tightly gripped thereby, and then bent 55 around either or both of the extensions 9, giving the desired bend or curvature to the wire. It is, of course, apparent that the curvature is varied by the position of the wire relative to the ends of the extensions. 60

It is the purpose of this invention to provide jaws for a vise which will make it a great deal more useful by increasing its range of work. It will enable work to be done right on the vise with less effort than 65 must now be done on an anvil with greater time and care.

The conical projections will enable one to make any kind of curve or hook desired without the use of an anvil. To make a small 70 curve or sharp bend the small end of the projection may be used. To make a larger circle or bend the larger diameter of cone may be used, and if it would be desired to make one still larger, the wide part of cones 75 could be used, but it would not be necessary to bend the wire down so hard but only sufficiently to form the diameter desired.

A continuous spiral could be made by placing a wire or rod between the cones at 80 the point desired, bending, loosening the grip, taking another purchase, and so continuing to the point desired.

If it is desired to make a staple, all that 85 is necessary is to place a piece of wire between the points and bend or hammer down and the staple is done. A piece of wire may be formed into a ring or link with ease. For holding rings, furls, bands, etc., while working on same it would be very 90 handy.

A vise with extensions of this kind on the jaws would be very handy in the blacksmith shop, tinsmith, or for any metal workers 95 and would be a great convenience on the farm or around the home.

Various slight changes might be made in the general form and arrangement of the parts described without departing from the invention, and hence I do not limit myself 100 to the precise details set forth, but consider myself at liberty to make such changes and

alterations as fairly fall within the spirit and scope of the appended claims.

I claim:

1. A vise, comprising a pair of jaws, and conical extensions projecting from the jaws, said extensions having surfaces in alignment with the gripping surfaces of the jaws.
- 5

2. A vise, comprising a pair of jaws, and conical extensions projecting from the jaws at one end thereof, said extensions having 10 surfaces in alignment with the upper and gripping surfaces of the jaws.

THEODORE SZYLDEROWICZ.
